UNITED STATES PATENT OFFICE

118,392

DESIGN FOR A COMBINATION EVENING AND STREET DRESS

Vincent Scappaticcio, New York, N. Y.

Application November 30, 1939, Serial No. 88,569

Term of patent 3½ years

To all whom it may concern:

Be it known that I, Vincent Scappaticcio, a citizen of the United States, residing in New York city, in the county of New York and State of New York, have invented a new, original, and ornamental Design for a Combination Evening and Street Dress, of which the following is a specification, reference being had to the accompanying drawings, forming part thereof.

Fig. 1 is a front view of a combination evening and street dress showing my design;

Fig. 2 illustrates Fig. 1 with the upper skirt portion forming the tunic omitted;

Fig. 3 illustrates Fig. 1 with the lower skirt portion thereof omitted.

The back of the combination evening and street dress is conventional.

I claim:

The ornamental design for a combination evening and street dress, substantially as shown and described.

VINCENT SCAPPATICCIO.
